CALIFORNIA

DENTAL CABINET

Application filed July 7, 1930. Serial No. 486,316.

This invention belongs to the class of dental or toilet appliances, being a cabinet with appurtenant parts, holders and compartments for tooth brushing, cleaning and treating appliances and materials.

The objects of the invention are: to provide a container or cabinet in or on which the various articles pertaining to tooth cleansing, oral treatment or other toilet procedures may be arranged for protection and convenience, having the characteristics of cleanliness, compactness, ease of removal and restoration of the contained objects; firmness on its base, having a plurality of means for its disposition and location, together with a pleasing appearance, and for preventing moisture from passing to exterior objects; and to produce an appliance of this character in which the several interior portions and divisions may be easily separated without use of time or tools for cleaning or other purposes.

Other objects will appear as this description proceeds.

This invention is an improvement of, or a departure from, the subject-matter of our previous application for a dental cabinet, Serial Number 364,614, filed May 20, 1929.

With the above and other objects in view, this invention consists in the new and useful provision, formation, construction, combination and interrelation of parts, members and features, all as hereinafter disclosed, shown in the drawings and finally pointed out in claims.

35 In the drawings:

Fig. 1 is a front elevation of the cabinet with the door, or closure open, contents of our improved cabinet exposed;

Fig. 2 is a front elevation, door or closure, closed;

Fig. 3 is a vertical section on line 3—3 of Fig. 2;

Fig. 4 is a vertical section of same on line 4—4;

Fig. 5 is a side elevation, same, interior parts in dotted lines;

Fig. 6 is a fragmentary cross section on line 6—6 of Fig. 1;

Fig. 7 is an isometric perspective of one inner compartment of the cabinet;

Fig. 8 is a variant of the form shown in Figures 1 to 5 inclusive, having the tooth brushes mounted on the outer surface of the closure instead of the inner surface; and

Fig. 9 is a vertical elevation, in section, of the tooth-pick compartment and the inner rim around the opening thereof.

As shown, the cabinet is a casing, preferably of thin metal, the bottom section being larger than that at the top. The cabinet is without an upper wall or top covering, this portion being left open for ventilation and drying of moist appliances. It is adapted to stand on end, or to be hung from a special bent screw support in the back, or over a nail or screw by means of a hole appropriately located in the rear wall.

The rear wall, A, that one opposite the door D, is higher than the other walls, rising in an upward curve from edges to middle. Hole 12 is formed adjacent the upper edge of the curved extension and is for hanging the cabinet if so desired.

Walls B and C, forming opposite sides of the cabinet, have their front edges sloped from the bottom upwards, being narrower at the top than the bottom. The closure D is a door, swinging on a pair of pintles 15—15, fixed on the forward edge of side C. When the door is closed it is a cabinet wall which slopes inward and upward. Receptacles F, fastened on a face of the door and drip-pan f, underneath holders F, form brush-holding means, whereof the bottom portion is adapted to catch any drip from the brush-heads which follows to the handles and downward by capillarity into the drip-pan f. Any accumulation of moisture in the pan f gradually evaporates as the entire cabinet is open at the top for air circulation. In this manner, dampening of the interior of the cabinet or its contents or any supporting surface is prevented.

A group of small receptacles is partitioned in a secondary or inner cabinet, G, in which the individual chambers 17, 18, 19 and 20 are arranged in stepped relationship, rising upward from front to back as shown. This arrangement makes the locating of any desired article and its withdrawal and replace-

ment easy. Neither light nor eye-glasses are needed to take out or put back the contents of this stepped group of receptacles as their separate positions are sufficiently defined to make a selection by touch a reliable manner of locating any one of the articles disposed therein.

The entire unitary group G, of containers is movable and may be taken from the cabinet 10 and replaced as desired. The rear wall 26 of the inner receptacle G is concaved away from rear wall A. The space thus provided accommodates the handle of a dental mirror 27, as shown. H is a small, shallow pan or vessel 15 having a stepped bottom portion 22, as indicated in Figs. 4 and 7. This vessel is placed in the cabinet and rests on the bottom thereof, the lower portion of the vessel bottom being in contact with the cabinet bottom while the 20 upper part of the vessel bottom, or the step made therein, rests on a raised portion J of the cabinet bottom. This part J extends across the front of the cabinet from wall B to wall C. It is formed by placing a strip 25 of heavy metal such as lead, across the bottom of the cabinet and folding an extension of the cabinet bottom over it or fastening it in any convenient manner. This strip is both a counterweight and a locking means for the inner removable parts of the cabinet, by inner edge 23.

From the form shown, it is evident that the cabinet, especially when empty of the various objects for which it is intended, has no 10 tendency to resist being overturned rearwardly or toward one of the sides, B or C. By placing the bottom weight J at the front of the bottom of the cabinet a gravity component is provided which resists overturning in any direction. At one side of the container H the group G abuts against and is retained by this metal strip J.

As shown, the inner edge of this weight 23 is higher than the bottom of the cabinet, and this edge, 23, provides a means of locking in the receptacle group G and the vessel H. First, group G is placed in position by pushing to the rear of the cabinet and then downwardly, so that it becomes held in four directions, viz, by the bottom of the cabinet, by the adjacent wall C, the rear wall A and the ledge 23 of weight J, respectively. The receptacle group therefore has only two directions of motion left, viz, toward the right wall B or upward. By placing stepped vessel H between the right-hand wall of the receptacle group and the right-hand wall B of the cabinet, the entirety is locked in place in the cabinet against motion in any direction except upwards against gravity. Even if the cabinet were turned upside down, the friction of the adjacent parts, pressed together, would hold them against dropping out.

The vessel H is for reception of a dentifrice tube, 24. The stepped bottom causes

the tube to fall backward toward the rear wall, so that merely placing the tube bottom in the vessel H and raising the tube to vertical will result in the tube dropping back to the rear as indicated in Fig. 5. The different receptacles in the inner group before described, are adapted to receive any preferred articles or substances, but, in general, dental floss; false teeth; chewing gum; tooth picks and the like, in groups, individual pieces or packages of the same or differing heights. Any of the compartments 17, 18, 19, 20, may have any preferred form, circular, rectangular, elliptical or other. Compartment 20 for tooth-picks is preferably provided with an inwardly-projecting rim around the top opening to direct the picks towards the center, as indicated in Fig. 6.

The brushes may be mounted on either side of the door; inside, as shown in Figs. 1 to 5 or outside as indicated in Fig. 8. The specific construction disclosed in our prior application before herein referred to, is maintained in this form of the invention, viz, the provision of one wall of the tooth-brush handle receptacle higher than the opposite wall. As shown in the figures, the handle-holding member F, fixed to the face of the door D is higher than the edge of the door. This construction aids placing the brushes in their receptacles when vision fails, either because of insufficient light or defective eyesight, the latter condition, accompanied by forgetfulness of the necessity for eye-glasses in a bath-room, being common. In placing the tooth-brush in its proper handle opening, it is only necessary to lift the lower end of the handle over the lower edge of wall D and let it strike against the upper edge of member F. This locates the end of the brush handle so that it can then be dropped into the receptacle provided for it.

The inward sloping of the front wall, or door, makes the whole cabinet more compact and adds to its appearance as compared with a vertical walled structure.

As mentioned, the cabinet may be held in several ways, a further one being by means of a bent metal angle L whereof one end fastens, or screws, into the wall of the room or of some article of furniture. A mating member K adapted to fit over the upwardly projecting end of L, is fastened to the rear wall A, as shown. The suspension means whereby the hole is passed over a convenient projecting object and the weighted ability to stand on any level surface, have been mentioned.

Having described our invention in connection with illustrative embodiments, forms, proportions and arrangement of parts, it will be understood that many variants thereof are possible to those skilled in the art, and our invention, in its broader aspects, is

not limited to the specific construction herein described and shown, as changes in the sizes, proportions, configurations, arrangements, assemblage, materials, juxtaposition and mechanical relations, as well as additions, omissions, substitutions, combinations and alterations of forms, parts, members and features, may be made without departing from the broad spirit of this invention.

10 Having thus disclosed our invention, we claim and desire to secure by Letters Patent:

1. A dental cabinet having a door, an upward and inward sloping wall, a holding means for tooth-brushes attached to said door and a drip pan under the brush handles.

15 2. A dental cabinet having a rectangular cross section, which diminishes in area as the top is approached, a door for said cabinet forming one wall thereof, brush-holding means attached to said door and a weighted bottom.

20 3. A dental cabinet having a rectangular cross section, which diminishes in area as the top is approached, a door for said cabinet forming one wall thereof, brush-holding means attached to said door and a weighted bottom, said weight being located adjacent and parallel to said door and forming a step 25 in the bottom for the cabinet.

30 4. A dental cabinet having a door, a stepped portion on the bottom adjacent said door, an inner receptacle fitting in a corner rearward of the door and locked against frontal motion by said stepped portion.

35 5. A dental cabinet having a door, a stepped portion on the bottom adjacent said door, an inner receptacle fitting in a corner rearward of the door and locked against frontal motion by said stepped portion, said receptacle having a group of compartments in 40 stepped relation upward and backward.

6. A dental cabinet open at the top having a slanting closure, brush-holding receptacles on said closure, a stepped bottom, and a vessel having a mating, stepped bottom adapted to rest inside and on the bottom of said cabinet, the bottom of said vessel being adapted to tilt rearwardly a tube placed end- 50 wise therein.

7. A dental cabinet having a plurality of containers held by group relationship against displacement in three directions and a bottom step holding same against displacement in a 55 fourth direction.

8. A dental cabinet having a plurality of containers held by group relationship against displacement in three directions and a bottom step holding same against displacement in a 60 fourth direction, said bottom step comprising a weight.

9. A dental cabinet having a plurality of containers held by group relationship against displacement in three directions and a bottom 65 step holding same against displacement in a

fourth direction, said bottom step comprising a weight, one of said containers having a bent wall providing accommodation for oral implements.

In testimony whereof, we have signed our 70 names to this specification at Los Angeles, Calif., this 2nd day of July, 1930.

CLARENCE A. LAWSON, SR.
